UNITED STATES PATENT OFFICE.

RAYMOND R. NORDSTROM, OF LITCHFIELD, MINNESOTA.

FIGURE WHEEL TOY.

Application filed December 2, 1926. Serial No. 152,196.

The present invention relates to improvements in toys and has for its primary object to provide an apparatus designed to impart oscillating movement to a toy structure.

5 A further object of the invention is the provision of a toy constructed to impart a reciprocating jigger movement to a figure.

A still further object of the invention is the provision of a wheeled toy designed to 10 impart vertical reciprocating movement to a figure or other toy structure directly proportional to the speed of the wheels.

Still another object of the invention is the provision of an amusement device which is 15 simple and durable of construction which will be efficient in operation and which can be manufactured at a relatively low cost.

Other objects and advantages of the invention will become apparent as the description progresses.

In the accompanying drawing forming a part of this specification and in which like reference characters are employed to designate corresponding parts throughout the 25 same:

Figure 1 is a side elevational view of a toy constructed in accordance with my invention,

30 Figure 2 is a top plan view of the same, and

Figure 3 is a vertical transverse sectional view taken on the line 3—3 of Figure 1.

Referring to the drawing, wherein for the purpose of illustration is shown the preferred embodiment of my invention, the numeral 10 generally designates a fragmentary portion of the draft tongue which is preferably rectangular in cross section. Secured on the upper portion of the tongue 35 adjacent its rear end is a screw eye 11 the purpose of which will become apparent as the description progresses.

Rigidly secured to the sides of the tongues 10 by means of staples 12 and projecting rearwardly of the tongues are a pair of complementary wheel brackets 13 embodying parallel forward arms 14 secured to the sides 40 of the tongues and offset parallel rear extensions 15 arranged in spaced relation rearwardly and laterally of the tongue. Formed on the rear extensions 15 and projecting inwardly are wheel spindles 16 adapted to rotatably support carriage wheels 17.

45 The carriage wheels 17 are preferably of disc formation formed with peripheral inwardly projecting flanges 18 and having cen-

tral transversely aligned openings and eccentrically offset aligned openings. Secured to the inner sides of the wheels in alignment with the offset openings and projecting inwardly in aligned projections are a pair of bearing sleeves 19, the inner ends thereof terminating in adjacent positions at the center of the structure.

50 Rotatably extended through the bearing sleeves 19 and arranged for rotary movement thereby is a transversely extending axle 20 formed with an offset crank 21 at its center. As shown to advantage in Figure 3, the longitudinal end portions of the axle 20 are 55 disposed in the bearing sleeves, while the offset crank 21 extends between the inner ends thereof.

Connected with the axle 20 adapted to be oscillated thereby is a brace bar 22 embodying a longitudinal flat metallic bar formed with a bearing sleeve 23 at its lower end rotatably mounted about the crank of the axle and having an angular seat portion 24 formed at its upper end.

55 A figure is mounted on the brace bar 22 embodying a plate 25 formed in the configuration of a torso and having arms and legs 26 and 27 respectively pivoted to the side portions of the torso.

60 The legs 26 are connected by means of pivot pins 28 with ears formed at the lower end of the torso, while the arms 27 are connected by pivot pins 29 with ears formed adjacent the upper ends thereof. The torso plate 25 is formed with a flange at its lower end which is pivoted or otherwise secured to the support plate 24 of the brace.

65 A link 30 extends from the eye 11 to the brace plate 24, the forward end of the link being formed with a loop 31 pivotally connected with the eye 11 while the rear end is formed with a rectangular loop 32 pivotally connected with a sleeve formed at the forward end of the base plate. This plate 70 maintains the figure in upright position so that the figure will describe a vertically reciprocating arc.

In operation, as the apparatus is drawn over the ground the wheels 17 will be rotated upon the spindle 16. As the wheels 75 rotate, they carry the movable axle 20 which describes a circular arc, reciprocating the brace bar 22 and causing the figure to continuously swing upwardly and downwardly 80 in a jigger movement. The operating movements of the figure correspond directly with

the speed of rotation of the wheels, and as the figure is operated, the arms and legs will swing in life-like movement.

While the reciprocating structure is illustrated in application with a dancing figure, it is also contemplated to apply the same in connection with reciprocating carriage bodies and similar apparatus. It is also contemplated to directly apply the structure upon the offset axle member 20 so that rotary movement of the carrier wheels will produce an oscillatory movement to the conveyance.

It is to be understood that the form of my invention herewith shown and described is to be taken as the preferred example of the same, and that various changes as to the shape, size and arrangement of parts may be resorted to without departing from the spirit of the invention or the scope of the subjoined claims.

Having thus described my invention, I claim:

A toy of the character described, comprising a draw bar, a pair of spaced rearwardly directed members attached to said bar and extending beyond one end thereof, a pair of wheel members carried by and supporting said rearwardly extending bars, a shaft eccentrically connecting said wheels, a supporting brace bar having one end pivotally connected with the central portion of said shaft, said bar being designed to normally maintain a substantially upright position and having its upper end extending at an angle rearwardly, a figure carried upon said rearwardly extending portion of the brace bar, means to provide an elongated slot at the upper end of said brace bar, and a connecting link having one end freely and slidably engaging through said slot for movement longitudinally of the brace bar and having the other end freely connected with said draw bar, substantially as described.

In testimony whereof I affix my signature
RAYMOND R. NORDSTROM.
